UNITED STATES PATENT OFFICE.

GEORGE J. ADAM, DECEASED, BY R. STUART ADAM, ADMINISTRATOR, OF CHICAGO,
ILLINOIS.

ANTISKIDDING TREAD DEVICE FOR YIELDING TIRES.

1,262,574.

Specification of Letters Patent.

Patented Apr. 9, 1918.

Application filed June 15, 1914. Serial No. 845,166.

To all whom it may concern:

Be it known that I, GEORGE J. ADAM, deceased, here appearing by administrator, R. STUART ADAM, a citizen of the United States, and a resident of Chicago, in the county of Cook and State of Illinois, have invented certain new and useful Improvements in Antiskidding Tread Devices for Yielding Tires; and I, by said administrator, do hereby declare that the following is a full, clear, and exact description thereof, reference being had to the accompanying drawings, and to the letters of reference marked thereon, which form a part of this specification.

This invention relates to improvements in antiskidding tread devices for yielding tires, such as pneumatic or cushion tires of soft rubber, and particularly to improvements in that type of such devices in which tough, non-metallic, flexible, compressible pads, such, for example, as leather or rubber pads, are provided for inducing friction between the tire and the surface with which it comes in contact. The object of my invention is to provide a novel construction of attaching means for the pads which is simple, economical, and at the same time highly efficient, and which permits the ready detachment of the pads singly, for the purpose of replacing them when they become old or worn out. The construction of attaching means to which the present invention relates is of the same general type as that disclosed in Letters Patent granted to me January 9th, 1912, No. 1,014,358, and in a prior application of mine filed February 23rd, 1911, Serial No. 610,216.

My invention also relates to a novel pad of the kind described, which, by reason of its form, combines a maximum of efficiency with a minimum of expense of manufacture.

The invention consists of the matters hereinafter described and more particularly pointed out in the appended claims.

In the accompanying drawings illustrating my invention:

Figure 1 is a top plan view of a pad provided with my improved attaching means 50 at each end thereof.

Fig. 2 is a view representing a partial longitudinal section in a plane indicated by the line 2-2 of Fig. 1.

Fig. 3 is a view representing a transverse section in a plane indicated by the line 3-3 of Fig. 1.

Fig. 4 is a top plan view showing my improved form of pad with the attaching means secured to one end thereof.

Figs. 5 and 6 are perspective views of the several parts of the attaching means to be hereafter more particularly referred to.

Fig. 7 is a view representing the link in side elevation and one of the parts of the attaching means in section, the former being shown in one of the positions during the process of attaching the same to the latter.

Referring now to that embodiment of my invention illustrated in the drawings, 12 indicates a pad, made of leather, hard, tough rubber, or other suitable non-metallic, tough, flexible material which tends to induce friction. The pad so far as the attaching means is concerned may be made of any form adapted for use in an anti-skidding tread device of the type described, and, as shown in Fig. 1, is in the form of a single straight, narrow strip. In Fig. 4 I have shown my improved form of pad but this will be described later as I shall first refer simply to the attaching means. The lateral edges of the pad adjacent its ends 14, 14, are provided with oppositely disposed, longitudinally spaced, pairs of notches 13^a, 13^a, 13^b, 13^b, within which the attaching devices are adapted to engage, as will presently appear. The parts 13, 13 of said lateral edges intermediate the said notches are curved in the arc of a circle.

The pad 12 is provided with attaching means at each end. Said attaching means, in each instance, comprises a flanged lower plate 15 having a base 15^a, which lies beneath the end of the pad, and which is provided with oppositely disposed, upright lateral flanges 16, 16, adapted for engagement with the arcuate parts 13, 13 of the lateral edges of the pad with their ends extending into the notches 13^a, 13^a, 13^b, 13^b, at the ends of said arcuate parts; and an upper plate 17 which rests on the top surface of the pad above the lower plate 15 and is engaged by the upper marginal parts 16^a, 16^a of the upright flanges 16, 16, which are bent inwardly and downwardly upon the same, as

best shown in Fig. 3. By this construction, the upper and lower plates are rigidly secured to the pad. In Fig. 1 the right-hand end of the pad shows the upper and lower plates as they appear before the upper marginal parts of the lateral flanges of the lower plate have been bent downwardly.

The base 15^a of the lower plate 15 is provided with an extension 18 having an aperture 18^a adapted to be engaged by the hook of a link 19. As shown, said extension 18 is inclined downwardly at an angle to the base 15^a so that the same will lie in contact with the surface of the tire to which my device is applied. On the upper surface of said extension 18 and surrounding the aperture 18^a is an annular rib 18^b having a laterally disposed groove 18^c. As illustrated in the drawings, said rib 18^b is preferably formed by pressing or stamping upwardly the metal of the extension.

The link 19 has two hooks 19^a, 19^b, the former adapted to be engaged within the aperture 18^a in the extension 18 and the latter adapted to be engaged by the chains applied to the tire and comprising the means for retaining the pads in position on the tread in a familiar manner. The end 19^a of the hook 19^a is not closed against the body of the link 19 but is spaced from the shank of the said link to allow the relatively thin part of the extension at the groove 18^c to pass between the same, when the link is brought into a position shown in Fig. 7, with its shank in the lateral groove 18^c and diametrically disposed with respect to the aperture 18^a. In this position of the link, the hook 19^a is capable of being brought into engagement with the aperture 18^a or to be disengaged therefrom. Such a position is an unusual or abnormal one for the link which is in any other position incapable of detachment from the extension 18 of the plate 15. By this construction the hook 19^a may be detached from the plate 15 by swinging the link into the position above described and the pad 12 may be removed and replaced by another one, whenever desirable, and for any reason as, for example, when the pad 12 becomes old or worn out.

As shown in the drawings, both of said hooks 19^a, 19^b lie on the same side of the shank of the link and in the same plane with each other so that the shank will lie in contact with the surface of the tire.

The construction described forms a simple, economical and efficient means for attaching the ends of the pads to the chains, by which the pads are held on the tire.

60 The lower plate 15 and the upper plate 17 frictionally engage the top and bottom surfaces of the pad-end by reason of the downwardly bent upper marginal parts 16^a, 16^b, of the lateral flanges 16, 16, and as shown in

the drawings, said upper plate is provided with an annularly disposed groove 17^a in its lower surface in order to increase the friction between the upper plate and the pad-end when the same is clamped thereto, the pad surface being upset into said groove 70 under the pressure employed in permanently attaching the parts together.

In Fig. 4 I have shown a novel form of pad for use in an anti-skidding device of the kind herein referred to. In said figure, 20 indicates the pad which has an intermediate tread part 21 and end parts 22, 22, extended beyond said tread part. The said end parts are like those hereinbefore described and are adapted to have applied to them the same kind of attaching devices, although the said pad may be used with other kinds of attaching devices. The intermediate tread part 21 of the pad is narrow at the middle and is wider at each side of the middle adjacent its ends.

The tread 21 of the pad has wide V-shaped notches 21^a, 21^b, formed in each lateral margin with the apex of each notch in the transverse median line of the pad. Said tread-part has edges 21^b, 21^b, at each end which are inclined toward each other so that the ends of the tread part are V-shaped. The end parts 22 of the pad form extensions of the tread part of the pad and are located at 95 the apex of the V-shaped end of said tread.

The V-shaped, notched, lateral edges of the pad grip the roadway when stress is thrown on the pad by reason of the tendency of the tire to slide or skid in the plane of its rotation, and the V-shaped ends of the tread of the pad grip the roadway and resist the tendency of the tire to slide or skid laterally.

My improved form of pad is highly efficient for use in an anti-skidding device of the kind described and is at the same time of economical construction. It is a species of the general type of pad described in Letters Patent No. 931,284, granted to Thomas I. Duffy, August 17th, 1909, but it has the particular advantage that only two attaching devices are required to connect each pad to the assembled anti-skidding device, whereas the pad of said Duffy patent requires four.

I claim as the invention:

1. An attaching device for a pad, said pad having an end part provided with longitudinally spaced pairs of oppositely disposed notches in its lateral edges, said device comprising upper and lower plates engaging respectively against the top and bottom surfaces of the end part of the pad, one of said plates having upright lateral flanges engaging the lateral edges of said end part of the pad and extending at their ends into said notches, said flanges having marginal

parts turned down and clamped against the other plate and means for attaching a link to one of said plates.

2. An attaching device for a pad, said pad having an end part provided with longitudinally spaced pairs of oppositely disposed notches in its lateral edges, said device comprising upper and lower plates engaging respectively against the top and bottom 10 surfaces of the end part of the pad, one of said plates having upright lateral flanges engaging the lateral edges of said end part and extending at their ends into said notches, said flange having marginal parts turned 15 down and clamped against the other plate, and one of said plates having an apertured extension.

3. An attaching device for a pad, said pad having an end part provided with longitudinally spaced pairs of oppositely disposed notches in its lateral edges which are arcuate between said notches, said device comprising upper and lower annular plates engaging respectively against the top and 20 bottom surfaces of the end part of said pad, the bottom plate having upright lateral flanges engaging the arcuate edges of said end part and extending at their ends into 25 said notches, said flanges having their upper marginal parts turned down on and 30 per

clamped against the top plate and the lower plate having an extension for the attachment of a link.

4. An attaching device for a pad, said pad having an end part provided with longitudinally spaced pairs of oppositely disposed notches in its lateral edges which are arcuate intermediate said notches, said device comprising upper and lower annular plates engaging respectively against the top 40 and bottom surfaces of the end part of the pad, the upper plate having an annular groove in its bottom face, the bottom plate having upright lateral flanges engaging the arcuate edges of said pad end part and extending at their ends into said notches, said flanges having their upper marginal parts turned down on and clamped against the top plate, and the lower plate having an extension for the attachment of a link. 45

In testimony that I claim the foregoing as the invention I affix my signature in the presence of two witnesses, this 2nd day of June A. D. 1914.

R. STUART ADAM,
Administrator of George J. Adam, deceased.
